DESIGN FOR A DISPLAY CONTAINER

Jean Otis Reinecke, Oak Park, Ill., assignor to
The De Vilbiss Company, Toledo, Ohio, a corporation of Ohio

Application November 22, 1947, Serial No. 142,730

Term of patent 3½ years

(Cl. D80—5)

To all whom it may concern:

Be it known that I, Jean Otis Reinecke, a citizen of the United States, residing at Oak Park, in the county of Cook and State of Illinois, have invented a new, original, and ornamental Design for a Display Container, of which the following is a specification, reference being had to the accompanying drawing, forming part thereof.

In the drawing

Fig. 1 is a front elevational view of a display container, showing my new design; and

The essential features of my design reside in the portions shown in full line.

I claim:

The ornamental design for a display container, substantially as shown, and described.

JEAN OTIS REINECKE.
